JAMES C. SMITH, OF ELYRIA, OHIO, ASSIGNOR TO THE MACHINE PARTS COMPANY, OF ELYRIA, OHIO, A CORPORATION OF OHIO.

VEHICLE.

1,103,226.

Specification of Letters Patent. Patented July 14, 1914.

Application filed September 14, 1912. Serial No. 720,308.

To all whom it may concern:

Be it known that I, JAMES C. SMITH, a citizen of the United States, residing at Elyria, in the county of Lorain and State 5 of Ohio, have invented certain new and useful Improvements in Vehicles; and I do hereby declare the following to be a full, clear, and exact description of the invention, such as will enable others skilled in the art 10 to which it appertains to make and use the same.

My invention relates to improvements in vehicles, and more particularly to the class 15 of vehicles which are commonly known as invalid chairs or cripple machines, by reason of their adaptability to the transportation of cripples or invalids who are incapacitated in one way or another, but at the same time are enabled to propel a specially 20 constructed vehicle of the nature described, by use of the member or members which are intact.

In the form of my invention illustrated, I show a vehicle which is adapted to be operated by the lower limbs of an individual, 25 for example, by one whose body or limbs are such as to render him incapable of walking, but at the same time are of such a nature as to enable him to propel the vehicle through 30 the use of pedals.

Hitherto, as far as I am aware, it has been customary to use rigid connecting means between the pedals and the running gear. This has been necessary because no suitable 35 means have been combined with the other elements of the machine which would stand the pressure placed upon them, and at the same time perform the function of admitting of some changes in this connecting rod. 40 Moreover, it has been difficult to find means which could be operated by individuals of the character who deal with machines of this kind, for as a matter of fact, they are generally unskilled in mechanics, and frequently 45 lack the patience and discretion necessary to deal with mechanics.

It is highly desirable to construct a device 50 which will admit of an extension of the connection between the pedals and the crank shaft without impairing the rigid connection between the two. This is necessary because in the first place, the effects of particular maladies are different upon different persons, so that in addition to the fact that

the limbs of one person may be longer than 55 those of another, one of the limbs of one person may be longer than another, his weight may be so distributed that he can most effectively operate the pedals in a particular position, or his malady may be of 60 such a nature as to either interfere or prohibit altogether the operation of the pedals in a particular position. This will be better appreciated when it is understood that the 65 pedals are driven by the person seated in the chair and the chair is gripped by the body in one way or another in driving the machine.

I have aimed to produce a chair in which the pedals could be dropped lower and 70 moved forward, so as to change the path of the pedal in its operation, and at the same time produce connecting means between the pedal and the crank shaft which may be easily and readily changed by those 75 unskilled in mechanics, and which may transmit motion and power from the pedals to the crank shaft without loss of either, and without tearing the connection asunder. By 80 this arrangement I am enabled to produce a simplified and cheaper chair for the trade, as well as to greatly add to the comfort and happiness of those who employ vehicles of this nature.

Other objects of my invention and the invention itself will be clear from the particular description of the embodiment illustrated in the drawing.

Figure 1 is a side elevation of a vehicle showing an embodiment of my invention. 90 Fig. 2 is a plan view of the connecting means. Fig. 3 is a side elevation, showing a portion of the connecting means. Fig. 4 is a section through Fig. 2.

Referring now to the drawings and to the 95 particular embodiment of my invention illustrated therein, at 6 is shown the frame of a vehicle, such as an invalid chair, and at 7 and 8, wheels therefor. In the form shown, the wheel 8 is employed for steering and is mounted in a frame head 9 which is rotatable upon the frame and adapted to be turned by a steering lever 10. The front and rear wheels are connected by a backbone member 11 or by any other suitable 100 device. A seat 12 is preferably connected by springs such as shown at 13 to the frame 14, which is fastened by any suitable means

to the frame 6. The wheel 7 is mounted upon an axis 15 to which is connected a crank rod 16. At 17 I show pedals which are adapted to drive the running gear of the vehicle, and which are mounted in any suitable way in the frame. In the form shown, the pedals 17 are connected to the frame head 9 by rods 18, which may be pivoted to the said frame head as shown at 20 at one end, and at the other end to the pedal as shown at 19. The pedal is likewise connected to the crank shaft by any suitable extensible means, which will properly and effectively transmit motion and power from the pedal to the crank shaft. I prefer to use such means as are shown in the embodiment illustrated. A connecting rod is shown at 21 pivoted at 22 to the pedal, so that the pedal remains substantially horizontal, no matter what its position. By connecting the two rods to different ends of the lower part of these pedals, such as the web 23, I am enabled to keep the surfaces of the pedals substantially horizontal when the connecting means is expanded or contracted.

The connecting rod 21 consists in the form shown of two parallel rods 24 and 25, each terminating in a hook as shown at 26 and 27. A connecting member is shown at 28 having a hook 29 upon one end, which hooks over the crank shaft 16. A finger 30 is formed adjacent the hook as shown, and the crank 16 is clamped between the hook and is held in position by a set screw 31 threaded in the finger 30. The flange 33 is perforated at a number of places, as shown at 36, which perforations are adapted to receive the hooks upon the ends of the rods 24 and 25, as shown in Fig. 2. Upon one end of the link 28 a support 29' is formed being cut away at 30' to receive the rods 24 and 25. A clamp 31' also formed to receive the rods is mounted over them and clamped down by some suitable means, such as a bolt 60, holding the rods firmly in place with their ends in the holes in the link 28.

It will be seen that the rods are so proportioned that the distances between the hooks are the distances between the perforations 36, so that the hooks fit into adjacent perforations. When in this position, a clamp 40 which is slidably mounted upon the rods 24 and 25 is slipped to a suitable position upon these rods, and clamped down, holding the hooks firmly in the perforations, so that power may be readily transmitted through the rods. When the cripple desires to change the position of his pedal, either to drop it or to move it farther from the seat, he loosens the nut 61 upon the bolt 60, releasing the jaws of the clamp, removes the rod from the perforations and moves it to a suitable position, and slides the clamp up, reclamping the rods together and the hooks

firmly in the perforations. I may use any suitable form of clamp; I have illustrated this form, as it is most convenient for my purpose, since it is easily manipulated and difficult to destroy. It will also be apparent that numerous and extensive departures from the form and details of the embodiment here used, may be made without departing from the spirit of the invention, this form being shown for the purpose of clearly illustrating an embodiment of such invention. 70 75

I claim:

1. In a device of the class described, the combination with the running gear of a vehicle including front and rear wheels, means for operating said running gear including a crank shaft, a perforated member pivoted thereto, said member having a plurality of perforations therein, a pedal, a plurality of rods connecting said pedal and said member, each rod having a hook at one of its ends to hook in the perforations in said member, and means to clamp said rods together. 80 85 90

2. In a vehicle, the combination with a front wheel, rear wheels, a frame on said wheels, a crank shaft for rotating said rear wheels, a seat in said frame, a pedal operable from said seat, a frame head on said front wheel, a rod connecting said pedal to said frame head, a pair of rods connected at one end to said pedal and provided with hooks on the other end one of said rods being longer than the other, a connecting link provided with a hook upon one end which hooks over said crank shaft, means to fasten said crank shaft in said hook upon said link, permitting the crank shaft to turn in the hook, a bearing member upon the other end 95 100 105 of the link and substantially perpendicular thereto provided with bearing surfaces for said rods and means to clamp said rods to said bearing surfaces, said connecting link being provided with perforations into which the hooks upon the rods enter when the rods are clamped thereto. 110

3. In a vehicle, the combination of a front wheel and a pair of rear wheels, a frame on said wheels, a crank shaft for rotating said rear wheels, a seat in said frame, a pair of pedals operable from said seat, a frame head on said front wheel, a rod connecting each pedal to said frame head and pivoted thereto, a pair of rods connected at one end to each of said pedals and provided with hooks on the other end, one of said rods being longer than the other, a pair of connecting links, one associated with each of said pairs of rods and provided with a hook upon one end which hooks over said crank shaft, means to fasten said crank shaft in said hook upon said link, permitting the crank shaft to turn in the hook, a bearing member upon the other end of each of the 115 120 125 130

links and substantially perpendicular thereto, provided with bearing surfaces for said rods and means to clamp said rods to said bearing surfaces, said connecting links being provided with perforations into which the hooks upon the rods enter when the rods are clamped thereto, said rods and connecting links being adjustable with respect to

each other to adjust the pedals upwardly and rearwardly simultaneously. 10

In testimony whereof, I affix my signature in the presence of two witnesses.

JAMES C. SMITH.
